UNITED STATES PATENT OFFICE.

WILLIAM H. WILDER, OF NORTHAMPTON, MASSACHUSETTS.

DESIGN FOR A STOVE.

SPECIFICATION forming part of Design No. 22,143, dated January 17, 1893.

Application filed September 9, 1892. Serial No. 445,458. Term of patent 14 years.

To all whom it may concern:

Be it known that I, WILLIAM H. WILDER, a citizen of the United States, residing at Northampton (Florence,) in the county of 5 Hampshire, State of Massachusetts, have invented and produced a new and original Design for Oil and Gas Stoves, of which the following is a specification.

The accompanying drawing represents a 10 stove embodying my design.

The leading feature of the design resides in the configuration of the turret or top which 15 surmounts the drum of the stove.

A represents the drum and above this drum 15 is the top of the stove of turret shape having

a flaring ornamental base *a*, extending from the top of the drum inwardly to a cylindrical center *c*, and above this center is a cap or top projecting slightly beyond the center and extending inwardly and upwardly in a curved 20 line to an ornamental center piece.

I claim:—

The design for a stove herein described and shown.

In testimony whereof I affix my signature in 25 presence of two witnesses.

WILLIAM H. WILDER.

Witnesses:

CHAS. E. FREY,
HATTIE M. GATES.
